UNITED STATES PATENT OFFICE

2,007,570

NEEDLE LUBRICATING MECHANISM

Otto F. Hoppe, Frankfort-on-the-Main, Germany,
assignor to United Shoe Machinery Corporation,
Paterson, N. J., a corporation of New Jersey

Application March 24, 1934; Serial No. 717,212
In Germany April 12, 1933

7 Claims. (Cl. 112—43)

The present invention relates to needle lubricating mechanism for shoe sewing machines, and is herein disclosed as embodied in a curved hook needle outsole stitching machine such as illustrated and described in the patent to Ashworth No. 1,169,909, dated February 1, 1916. Machines of this type run at comparatively high speed and when operating on heavy and hard stock frequently give trouble on account of the overheating and ensuing breakage of the needle occurring when operating upon stock of this kind, particularly if temporarily attached to the lasted shoe by cement.

The objects of the present invention are to provide a needle lubricating mechanism, particularly adapted for use in outsole stitching machines which will be of simple and durable construction and which will act with certainty to supply the requisite amount of oil to the needle to thoroughly lubricate that portion of the needle passing through the work.

With the above objects in view, an important feature of a lubricating mechanism embodying the present invention is that the oil is applied to that part of the needle which projects forwardly from the needle guide so that the oil reaches the point of the needle and, in entering the needle hole in the work, the needle point is well lubricated and the leather fibres and cement in the stock are prevented from adhering thereto.

Other features of the invention consist in certain constructions and arrangements of parts whereby the needle lubricating device is supported in the proper position adjacent the path of the needle, is moved towards and from the needle at the proper time during the stitch forming cycle, and is supplied in a certain and reliable manner with the requisite amount of oil.

The several features of the invention will be readily understood by those skilled in the art from the following specific description of an embodiment of the invention taken in connection with the accompanying drawing in which Fig. 1 is a detail view showing in sectional elevation so much of the outsole stitcher disclosed in the Ashworth patent above referred to as is necessary to illustrate the connection of the present invention therewith; and Fig. 2 is a view in front elevation of the needle lubricating mechanism illustrated in Fig. 1 with a few of the adjacent parts of the sewing machine shown in dot and dash lines.

In Fig. 1 the curved hook needle of the machine, indicated at 2, is secured in a needle segment 4 which is actuated from a crank 6 on one of the driving shafts 8 of the machine through a

link 10, a lever 12, one end of which is connected to the crank 6 by the link 10, and a link 14 which connects the other end of the lever 12 with the needle segment. The needle guide, indicated at 16, is mounted concentrically with the needle and is actuated from a cam on the driving shaft 8 through a bell crank 18, one arm of which engages the cam and the other arm of which is provided with a gear segment meshing with a gear on a shaft 20, which shaft is provided with a gear meshing with a gear segment on the hub of the needle guide. These connections for actuating the needle and needle guide and all other parts of the machine disclosed in the drawing, and not hereinafter specifically described, are the same in construction and mode of operation as in the machine of the Ashworth patent above referred to.

The needle lubricating mechanism illustrated in the drawing as embodying the features of the present invention comprises a needle lubricating brush indicated at 22. This brush is mounted to reciprocate towards and from the path of the needle in a casing or bracket 24 which is secured to the machine frame in such a position that the brush 22 moves towards and from the path of the needle and contacts with the portion of the needle projecting forwardly from the needle guide while the needle is in substantially its extreme retracted position. For actuating the oil applying brush 22 in the proper timed relation to the movements of the needle and needle guide, it is secured to one end of the wire 26 of a Bowden wire mechanism, the sheath of which extends between the casing 24 and a bracket 28 on the machine frame. The other end of the wire 26 is adjustably connected to a spring pressed plunger 30 mounted to slide in the bracket 28 and provided at its lower end with a roll engaging a cam 32 on the driving shaft 8. The adjustable connection between the wire 26 and the plunger 30 comprises an adjusting screw 34 connected to the wire 26 and screwing into the plunger 30. By means of this adjustable connection, the limit of the advancing movement of the oil applying brush 22 may be regulated as desired. The adjusting is maintained by a lock nut 36 threaded on the screw 34 and bearing against the upper end of the plunger 30.

To enable the path of the brush to be adjusted relative to that of the needle, and also to permit the brush with its casing 24 to be moved away from the needle so as not to interfere with necessary repair operations or the insertion of a new needle or awl, the casing 24 is pivotally mounted

upon the machine frame, and is clamped in position by a clamping bolt 38.

The proper amount of oil is supplied to the oil applying brush in a certain and reliable manner

- 5 from a drip feed oil cup 40 of well known construction which is mounted on the frame of the machine and connected to the interior of the casing 24, in which the brush 22 reciprocates by a conduit 42, the lower end of which at least
- 10 is sufficiently flexible to permit the movements above described of the casing about its pivotal support.

The nature and scope of the invention having been indicated, and an embodiment of the invention having been specifically described, what is claimed is:

1. The combination, in a shoe sewing machine provided with a curved hook needle and a needle guide, of means for applying oil to the portion 20 of the needle extending forwardly from the needle guide.

2. The combination, in a shoe sewing machine provided with a curved hook needle and a needle guide, of a needle oiling device, and means

25 acting in timed relation to the movements of the needle and needle guide for applying oil to the portion of the needle extending forwardly from the needle guide while the needle is substantially at the limit of its retracting stroke.

30 3. The combination, in a shoe sewing machine provided with a curved hook needle and a needle guide, of a needle oiling device, and means for

moving the oiling device into engagement with the portion of the needle extending forwardly from the needle guide.

4. The combination, in a shoe sewing machine provided with a curved hook needle and a needle guide, of a needle oiling device, and mechanism for moving the oiling device into and out of engagement with the needle in timed relation to the movements of the needle and needle guide comprising a cam and a Bowden wire interposed between the cam and the oiling device.

5 5. The combination in a shoe sewing machine provided with a curved hook needle and a needle guide, of a needle oiling device, a stationary casing 15 in which the oiling device is mounted to move into and out of engagement with the needle, and means for supplying oil to the casing.

6. The combination in a shoe sewing machine provided with a curved hook needle and a needle guide, of an oiling device, a stationary casing 20 in which the oiling device is mounted to reciprocate into and out of engagement with the needle, and an oil conduit connected to the casing.

7. The combination in a shoe sewing machine provided with a curved hook needle and a needle guide, of an oiling device, a stationary casing, 25 adjustable to permit access to the needle, in which the oiling device is mounted to reciprocate into and out of engagement with the needle, and means for supplying oil to the casing.

30 OTTO F. HOPPE.
